CLAIM

The ornamental design for a portable safety containment device for a standing child, as shown and described.

DESCRIPTION

FIG. 1 is an overall perspective view of a portable safety containment device for a standing child, showing my new design;

FIG. 2 is a front view thereof;

FIG. 3 is an elevational view, identical for both the right and left sides thereof;

FIG. 4 is a top view thereof;

FIG. 5 is a bottom view thereof; and,

FIG. 6 is a rear view thereof.
